Letters Patent No. 88,010, dated March 23, 1869; antedated March 4, 1869

IMPROVEMENT IN TRIPPING MECHANICAL DETENTS.

The Schedule referred to in these Letters Patent and making part of the same.

Be it known that we, STEPHEN CHESTER, of the city, county, and State of New York, and CHARLES T. CHESTER, of the village of Englewood, county of Bergen, and State of New Jersey, have invented a new and improved Mode of Tripping Detents in Machinery; and we do hereby declare that the following is a full and exact description of these improvements, reference being made to the accompanying drawings, of which—

Figure 1 represents the complete machine, omitting the arm, or rod that carries the power to the desired place for using it; and

Figures 2, 3, 4, and 5, separate portions, in detail, similar letters being used to designate similar parts.

The object of our invention is to obtain, from the exertion of a very small force, the liberation of powerful mechanism, and we have illustrated one particular combination for a particular purpose, though the combination we desire to patent is applicable also, generally, to all machinery where a small power is required to liberate a heavy weight.

Our illustration represents the combination of the detent with an electro-magnetic apparatus.

Where this power is to be exerted at a great distance, it is well known that it is much reduced in effect.

The friction that a common detent would occasion, where a large weight was employed to strike a heavy blow with a large hammer, would make it necessary to employ a strong force to liberate it, so that recourse has been had to the addition of a falling ball, which, being liberated by a small force, descends, and, accumulating force in its descent, finally strikes a heavy blow on the second detent, which liberates the machinery. An appreciable time is occupied, in this arrangement, for the hammer to acquire this force by its descent, so that rapid effects cannot be produced where it is used. But, more particularly to describe the parts that compose our detent, and their relations to one another, we refer to fig. 1.

The frame A supports a train; consisting of one wheel, c, and one pinion, D, with its shaft F.

This shaft extends outside of the frame, and is firmly fastened to the arm G.

This arm has a projecting pin, i, and this pin passes through one end of the rod V V, fig. 4.

The other end of this rod engages with the arm W, fig. 5.

This arm projects from a rod, which terminates in a hammer, Y, and may be made to ring a bell, or perform any other required service.

Thus far the simple action of the machine is this: The weight driving the main wheel, which communicates motion to the pinion, this pinion carrying a crank-arm, (outside the frame,) motion is given, through the pin i and the rod V V, in the usual reciprocating direction.

We now come to our particular device for stopping

and starting this action, and restoring the parts to their position of rest.

As an example of small force, we use the fine wire magnet B, with its armature E, its lever T continued and extended in Q.

It is evident that Q will vibrate from right to left, under a small magnetic influence, or by the pulling of a string, or other mechanical movement.

Q carries on its face two springs, m' m", terminating in V-shaped catches.

Small upright pins n' n", also attached to the lever Q, have set-screws o' o" to pass through them, and these screws press against the flat side of these springs, and thus set them more or less close to one another.

These spring-catches engage the barbed end of a steel projection on a lever, J, and hold this lever up.

When Q goes to the right, the barbed end engages in the catch of spring m'. When Q goes to the left, the other side of the barbed end engages with m".

Now, these two spring-catches are practically so made that one is a little below the other, and the lever Q, through these two catches, holds the barbed end, first on the highest catch, and then when the lever Q moves, the spring-catch detaches itself from the barbed end, which drops by reason of the weight of the lever J, but it catches instantly again on the lower spring-catch, and remains there until the lever Q moves back again, and then it drops off, and the lever J falls upon the pin r, which projects from lever Q.

Now, the lever J carries a strong, well-supported steel roller K.

As long as the barbed end remains caught, either on m' or m", the crank-arm G is pressed against the roller K, but, as soon as the lever J drops to r, then the roller, dropping with it, slides over the face of G, and thus this crank-arm being liberated, flies around until it nearly performs its function in relation to the hammer Y.

Before it completes its revolution, however, it engages, through its projecting end, fig. 2, with the cam L, which is firmly fastened to lever J, and this cam is so shaped that the continued rotation of G draws up the lever J, so that the barbed end moves into a position higher than its engagement with either of the adjustable spring-catches, and almost at the same instant that G strikes the roller K, which stops it, it slips off of the cam L, and thus allows the lever J to drop down gently into an engagement, through its barbed end, with either m' or m", according as the lever Q is to the right or to the left. Thus the crank-arm G is firmly caught, and recoil and jar are prevented.

It is evident that, for some purposes, we may reverse the relation of these parts; and by placing (fig. 3) the cam A on the shaft F, and the lifting-arm B on the lever J, we can lift the lever, to replace it as before.

The face of G, which strikes against and moves against

the roller, must be shaped so as to correspond with the arc of a circle, described from the fulcrum U, of the lever J.

The movement of the lever J thus does not increase or diminish the pressure of G against the roller, and it follows that no increase of force applied to G will influence the friction of the barbed end upon the spring-catches $m' m''$.

What we claim, therefore, and desire to secure by Letters Patent, is—

1. The adjustable spring-catches arresting the detent, by means of which the delicacy of the trip is adjusted, and the wear of the parts compensated for.

2. The combination of the lever Q with its adjustable spring-hook, or hooks, the barbed detent, the lever J, the roller K, the crank-arm G, the cam L, which, acting together, allow a small force to liberate machinery, and which restore themselves to their relative positions in rest, substantially as described and for the purposes set forth.

STEPHEN CHESTER.
